UNITED STATES PATENT OFFICE.

FRANK R. McBERTY, OF NEW ROCHELLE, NEW YORK, ASSIGNOR TO WESTERN ELECTRIC COMPANY, OF NEW YORK, N. Y., A CORPORATION OF ILLINOIS.

AUTOMATIC TRUNK SIGNALING SYSTEM.

1,117,511.

Specification of Letters Patent.

Patented Nov. 17, 1914.

Application filed September 19, 1910. Serial No. 582,677.

To all whom it may concern:

Be it known that I, FRANK R. McBERTY, citizen of the United States, residing at New Rochelle, in the county of Westchester and State of New York, have invented a certain new and useful Improvement in Automatic Trunk Signaling Systems, of which the following is a full, clear, concise, and exact description.

10 My invention relates to telephone exchange systems of that class wherein lines from a semi-mechanical exchange, or from a subscriber's automatic station, terminate in a manual exchange, and has for its object 15 to provide means whereby the manual operator may automatically be informed of the designation of the line with which connection is desired.

In the specific form of my invention 20 shown herein the object thereof is to provide a number indicator for the manual exchange and means for automatically connecting the same to any line over which a call is transmitted from an automatic exchange, such indicator being adapted to display the number 25 of the line wanted in response to the sending or calling apparatus which in the automatic exchange determines the operation of the selecting mechanism.

30 In the operation of the system in which there is employed appropriate automatic calling apparatus, when the operator at the automatic station or at the semi-mechanical exchange calls a line, she operates appropriate calling apparatus which is adapted to 35 select the number of the called subscriber's line. In case the line thus selected terminates in an automatic exchange the apparatus at that exchange will be operated automatically to select a line corresponding to 40 the number set up on the apparatus at the calling end of the line. In case, however, such a line terminates in an exchange of the manual type it is necessary or desirable to 45 provide at that exchange some means governed by the conditions which select the line through the automatic exchange, which will operate to designate upon suitable indicating apparatus the number of the called line.

50 As one means of accomplishing this signaling I provide at the manual exchange a series of successively operated devices which are associated with the cord circuits at such exchange in such a manner that when the 55 line selecting apparatus at the semi-me-

chanical exchange or the subscriber's automatic station has been operated, said devices will operate in regular sequence to complete the circuits necessary for displaying the signal designation of the line desired. More 60 specifically the means for thus signaling the operator at the manual exchange embraces a plurality of successively operated registers each adapted to be moved through a definite distance to set up for display upon suitable 65 indicators one digit of the called number, the extent of movement of each of said registers being controlled by the calling apparatus. A line relay associated with each of said lines at the manual exchange is energized by 70 the closing of the talking circuit and thereby causes the operation of sequence switches and an automatic trunk line finder, the operation of which and the sequence switches establishes a circuit operatively connecting 75 the first of said registers with the calling or sending apparatus. At the completion of the operation of each of said registers, except the last, there is completed a circuit for the operation of the succeeding one thereof, 80 and the operation of each determines the display of a signal indicating one digit of the called number.

One feature of my invention involves 85 means whereby a single indicating apparatus may be successively utilized to care for all of the calls coming over a plurality of lines terminating in one operator's switchboard position.

Another feature of my invention provides 90 means whereby when a particular cord has been selected for receiving a call and connected with the indicating apparatus the remaining cords in the same operator's position will be prevented from becoming associated with the numerical indicating apparatus.

My invention also includes means associated with the signaling system whereby when a cord has been seized and prepared to 100 receive the call a lamp will be lighted to designate to the operator which cord is in use.

My invention also involves as one of its features a means whereby when the call for 105 one line has been completed and the talking circuit therefor set up by the operator at the manual exchange the numerical indicating apparatus will be released from connection with the particular cord and rendered free 110

to receive a call over any one of the remaining lines.

In the drawings in which the system is for convenience illustrated in connection with a semi-mechanical exchange—Figure 1 is a diagram illustrating so much as is necessary for an understanding of my invention of the sending or controlling apparatus and circuits therefor, at the originating exchange. Figs. 2, 3 and 4 when taken together form a diagram of the circuits and apparatus of the signaling means at the incoming exchange and show one form of my invention.

Like reference numerals designate like parts throughout the drawings.

In order to better understand the operation of the system brief reference will first be made to the various apparatus as used in connection therewith.

Referring first to the sending or controlling apparatus, the same comprises generally a set of counting relays and a series of controlling switches or keys, together with a stepping relay for operating the counting relays in succession to close contacts in circuit with the switches or keys, and a cut-off relay adapted when the circuit is closed simultaneously by one of the counting relays and the particular key depressed to open a controlling circuit and thereby control apparatus in said circuit at the distant end thereof. As shown there are two series of counting relays, one series comprising relays 1 to 8, inclusive, which are adapted respectively to close contacts 61 to 68 in circuit with keys 51 to 58 and the cut-off relay 23. The other series of counting relays 11 to 18, inclusive, is operated in alternate succession with said relays 1 to 8 to close circuits therefor. These two series of relays may be extended to include any desired number. The stepping relay 24 is arranged to be energized and deenergized intermittently during the movement of the registers of the numerical indicating apparatus, as will hereinafter be explained. Upon its first energization it closes contact 25 which completes a circuit from a battery 26 through contact 34, auxiliary counting relay 11 and back contact 28 of counting relay 1, thereby energizing relay 11 which closes a locking circuit for itself by way of its contact 29 and also closes contact 30. When the stepping relay is then deenergized its armature falls back closing contact 31, thereby completing a circuit for counting relay 1 from battery 26 through contact 32, winding of relay 1, back contact 33 of the second auxiliary relay 12, contact 39 of the first auxiliary relay 11 to ground and back to battery. Relay 1 is thereupon energized and it like relay 11 closes a locking circuit for itself by way of contact 61 and at the same time prepares through the contact 28 a circuit for the next counting

relay of the other series. As before stated, however, contact 61 is also in circuit with the cut-off relay 23 and the first of a series of controlling switches or keys 51 so that if this key had been depressed, the operation of the first counting relay 1 would cause the cut-off relay 23 to open the circuit of the stepping magnet 24. It, therefore, follows that the number of impulses of current flowing through the winding of stepping relay 24 before the cut-off relay 23 shall open the circuit of the stepping relay, depends upon the particular controlling switch or key which had been depressed. The stepping relay is included in a loop which may be associated with the trunk line conductors 35 and 36 leading to the manual exchange shown in Figs. 2, 3 and 4, suitable switch contacts 37 and 38 being provided for making the connection when it is desired to signal a particular number of the manual exchange.

The signaling system includes also sequence switches, the general functions of which are to establish in definite order at successive stages of the operation the various circuits required to bring into service the various apparatus in proper sequence. A form of sequence switch which I find convenient for this purpose comprises generally a movable switch operating member, a number of circuit changers actuated in sequence as said member is moved from one position to another, an electromagnet and motor mechanism operated or controlled by said magnet for advancing said movable member. In each position to which the movable member of a sequence switch is advanced a circuit or set of circuits is established by which a given operation of the apparatus under control is made possible, and at the same time another circuit is established whereby the motor magnet of the sequence switch may be actuated to move automatically the sequence switch to its next position to establish a new set of circuits. Sequence switches are, however, known to the art and therefore need not be further described herein. It should be understood, however, that my invention is not limited to use in connection with any particular form of sequence switch, but may be used in connection with any form which may be most suitable and convenient or with any apparatus performing equivalent functions.

In the circuit drawings the switch strings of the sequence switches are not shown in their actual arrangement, but are so located as to give the clearest arrangement of circuits. The positions of the sequence switch in which any of its contacts are closed are indicated by numbers placed adjacent to such contacts; each contact being open in all positions except those indicated by the

adjacent numbers. In the case of the special contacts shown upon the drawings at 156 and 266 the numbers are placed on the opposite side of the contact anvil and indicate 5 positions in which such contact is open, said contact being closed continuously while the rotary element of the sequence switch is in transit between the positions indicated.

In the operation of the system the various 10 digits designating the desired line are registered at the incoming end of the trunk line through the agency of a series of switching mechanisms which register the line designation by means of groups of lamps or other 15 signal devices, the movement of the switching devices being controlled by electrical effects set up by their own movement, such electrical effects operating and being determined through the sending or controlling 20 apparatus hereinbefore described.

The switching devices or registers referred to are shown in this disclosure of my invention as sequence switches. By reference to Fig. 4 of the drawings it will be seen that 25 they each comprise the usual power and holding magnets, sequence switch contacts and the usual special sequence switch contacts. They each in addition, however, comprise a commutating device adapted to make 30 and break a circuit once for each position which the switch is adapted to take. Since sequence switches of this character are known to the art, the structure of these registers will sufficiently appear in the description of 35 the operation thereof and no further description of the registers themselves is thought to be necessary. It should be noted, however, that my invention is not confined to use in connection with any particular form of register and such registers may be of any suitable or convenient form and still come within the scope of my invention. In practice 40 there will be as many of these registers employed as there are digits in the number of 45 the line called, and they will be successively operated to indicate the number desired in the manner hereinafter explained.

The cord in which the selected incoming 50 trunk terminates at the manual exchange is found and associated with the registers by means of the cord finding apparatus. This cord finding device is illustrated in Fig. 3 55 of the circuit drawing and embraces generally a rotatable brush carrying shaft 140 carrying brushes 141 which are adapted to traverse stationary contact members 142 arranged concentrically about said shaft. The shaft 140 carries at one end an iron disk 143 which is adapted to be drawn into frictional 60 driving relation with a constantly driven power shaft 144, by means of a power magnet 145. A holding magnet 146 located near the margin of the disk 143 is energized when 65 the circuit to the power magnet is interrupted to attract said disk and stop the ro-

tation of the brush carrying shaft 140. Mounted upon said brush carrying shaft 140 is a contact making arm 147 the outer end of which in the rotation of said shaft 140 travels over a notched or toothed plate 148 70 mounted concentrically with said shaft 140. As it travels over said plate said arm closes a contact through a spring 149. It will be noted that the spring 149 is so located that the circuit therethrough will be completed 75 only when a roller upon the outer end of the arm 147 is in one of the notches.

Referring now in detail to the operation of the system, we will assume that the switches 37 and 38 of the counting apparatus are hand-operated for convenience in explaining the operation, although in practice these switches will be operated automatically and mechanically in the ordinary course of a call. The battery 172 is shown 80 in several portions of the circuit diagrams on Figs. 2, 3 and 4 merely for clearness in illustrating the circuits and it will be understood that these several representations of battery are to be considered as meaning a 85 single battery, although if desired several batteries may be employed. The same is true of the battery 26 in Fig. 1. As shown in the drawings, Fig. 2, the conductors 35 and 36 of the trunk line terminate in springs 90 101 and 102 of the cord sequence switch 155, which switch is initially controlled by calling conditions in the trunk lines. Assuming now that the call has been started at the semi-mechanical exchange over the trunk 95 line conductors 35 and 36 there will be a circuit established through the line relay 103 which circuit may be traced from battery 172, back contact and armature 104 of what is known as the second supervisory relay 105, line relay 103, conductor 106, conductor 107, sequence switch contact 101, 100 trunk conductor 35, contact 37, back contact 45 of cut-off relay 23, stepping relay 24, contact 38, trunk conductor 36, sequence switch 105 contact 102, conductor 108, armature 109 and its back contact of relay 105 to ground 110 and back to battery. Upon the energization of said line relay its armature will be pulled up closing its front contact and thereby 115 establishing a circuit through the winding of the cord sequence switch 155, which circuit may be traced from battery 172 through the power magnet of said cord sequence switch, conductor 110, sequence switch contact 111, conductor 112, front contact and armature of the line relay 103 to ground and back to battery. This will cause the operation of said cord sequence switch 155 moving same from its first into its second position in which position it closes sequence switch contact 113 and establishes a circuit through the power magnet of the position sequence switch 265, causing same to move 120 from its first into its second position. This 125 130

5 circuit may be traced from battery 172 through the power magnet of the position sequence switch, contact 288, conductor 189, sequence switch contact 118, front contact and armature of the line relay 103 to ground and back to battery.

10 In its second position the position sequence switch 265 completes a circuit through the winding of the power magnet 145 of the cord finder, from battery through the power magnet 145, back contact 190 of the test relay 194, sequence switch contact 292 to ground and back to battery. The energization of the power magnet 145 causes 15 the brushes 141 to rotate until they are brought into contact with contact members 142, one of which is grounded through sequence switch contact 114. When the brushes reach this position there will immediately be completed a circuit through the test relay 194, such circuit being traced from battery 172 through the relay 194, interrupter 147, the lower cord finder brush 141, the corresponding contact member 142, conductor 201 sequence switch contact 114 to ground and back to battery. The energization 20 of the relay 194 will open its back contact 190, thus interrupting the circuit through the power magnet 145 of the cord 25 finder and will close its front contact 203 which will complete a circuit through sequence switch contact 292 and the winding of the holding magnet 146, energizing said magnet to hold the disk 143 against further rotation. Also the energization of relay 194 30 completes a circuit through the position sequence switch 265, which circuit may be traced from battery 172 through the power magnet of said position sequence switch, sequence switch contact 201, conductor 205, front contact 203 of the test relay 194, sequence switch contact 292 to ground and back to battery. This causes the position sequence switch to move from its second into 35 its third position in which position there is completed a circuit for the cord sequence switch 155, which causes it also to move from its second to its third position, the circuit in this case being traced from battery 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 counting relay 1 to ground and back to battery. This energizes the cut-off relay 23 which by attracting its armature opens the contact 45 thereby opening the sending or controlling circuit and deenergizing the line relay 103 as soon as the ground is again removed from the conductor 217 by the further movement of the thousands register, which occurs when the register upon leaving its first or normal position has reached its second position; that is to say, the position in which the topmost of the series of contact devices associated with it is closed. Immediately upon the deenergization of the line relay 103 the energizing circuit for the power magnet 401 of the thousands register is opened at the front contact of the said line relay and the thousands register will thereupon stop and the first or top lamp of the thousands bank of lamps will be lighted. If, however, on the other hand, some other one of the switches, 51, 52, 53, 54, etc., had been closed for thousands selection control the thousands register would continue to move intermittently shunting the stepping relay 24 until the counting relay associated with the switch which had been closed is energized, when the cut-off relay will be energized and the thousands register stopped in the corresponding position as has been hereinbefore described. That is to say, if the switch 54, for example, had been closed the thousands register would have to four times shunt the stepping relay 24 before the action of the cut-off relay 23 will stop the thousands register to light the fourth lamp of the thousands bank of lamps. At the same time that the line relay by the retraction of its armature opened the energizing circuit through the power magnet 401 of the thousands register at its front contact, it closed a circuit at its back contact for the position sequence switch 265. This circuit, which may be traced from the battery 172 through the power magnet of the position sequence switch, the sequence switch contact 225, conductor 226, sequence switch contact 118, back contact of the line relay 103 to ground and back to battery, causes the position sequence switch to move from its third into its seventh position. This movement of the position sequence switch opens the sequence switch contacts 292 and 209, the opening of which is without effect at this time and also opens the sequence switch contact 214. The opening of the sequence switch contact 214 prevents a subsequent closure of the energizing circuit controlled by the line relay to the thousands register and the closure of the sequence switch contact 241 when the position sequence switch reaches its seventh position, shifts this energizing circuit to the hundreds register. It will be noted that the special sequence switch contact 266 of

the position sequence switch 265 is closed in the fourth, fifth and sixth positions of the sequence switch so that the position sequence switch upon leaving its third position continues to move until it reaches its seventh position, during which time the sequence switch contact 225 is opened but is again closed as the switch reaches its seventh position. The register apparatus is now ready to respond to the necessary operations to designate the hundreds digit of the line desired.

Following the operation of the cut-off relay 23 terminating thousands selection, the switches 32 and 34 are operated and the depressed switch of the group 51, 58 inclusive is released. These operations may be performed manually or by any suitable means but in practice it is preferable and customary that these operations be performed automatically and mechanically and in the regular course of the establishment of the connection. The opening of the switches 32 and 34 restores all of the locked up counting relays to their normal positions. The same operation which has opened the switches 32 and 34 has also opened the switches 37 and 38. After the counting relays have been restored to their normal position one of the switches 51 to 58 is closed for hundreds selection control and the switches 32, 34, 37 and 38 are again closed by any desired means and the sender apparatus is now in condition to control hundreds selection, the sender or controlling circuit being closed throughout, energizing the stepping relay 24 and the line relay 103, the cutoff relay 23 having been deenergized by the restoration of the counting relays. The operation of the hundreds register is substantially the same as that hereinbefore described of the thousands register and the details thereof need not be repeated. At the completion of the operation of the hundreds register the controlling circuit is again opened at the semi-mechanical exchange permitting the armature of the line relay 103 to again close the circuit at its back contact and complete the circuit for the succeeding operation of the position sequence switch 265. In this operation said sequence switch is moved from its seventh to its eleventh position and the tens register is brought into cooperative relation with the sending or controlling apparatus at the semi-mechanical exchange by the opening of the sequence switch contact 241 and the closure of the sequence switch contact 231. The operation of said tens register is a substantial repetition of that of those already described, there being completed a circuit at the end of its operation which will cause the movement of position sequence switch 265 from its eleventh to its fifteenth position in which the sequence switch contact 231 is

opened and the sequence switch contact 232 is closed whereby the fourth or units register may be operated to designate the last digit of the called number. Upon the completion of the operation of the units register the armature of the line relay 103 will again drop back completing the circuit for the operation of the sequence switch 265 and moving same from its fifteenth to its sixteenth position. In this position of the position sequence switch 265 there is established a circuit through the cord sequence switch 155, whereby said sequence switch is moved from its third into its eighth position by reason of the fact that the special contact thereof is closed between the third and eighth positions of said switch. The circuit in this case may be traced from battery through the power magnet of said cord sequence switch, sequence switch contact 119, conductor 237, sequence switch contact 238 to ground and back to battery. In this position of the parts the operator is now prepared to complete her call by inserting the plug 124 into the jack corresponding to the numbers indicated by the registering devices as hereinbefore described. In completing this connection the operator first makes the usual busy test over the tip of the plug, conductor 125, back contact and armature 126 of relay 127, primary winding of the induction coil 128, sequence switch contact 129 to ground. Upon finding that the line is not busy she inserts her plug fully into the jack. This operation completes a circuit from battery through a relay 127 to the sleeve spring of the line jack to ground through the usual cutoff relay. The energization of the relay 127 in this circuit establishes a circuit for the succeeding operation of sequence switch 155, which circuit may be traced from battery 172 through the power magnet of said sequence switch, conductor 110, sequence switch contact 120, conductor 130, front contact and armature 131 of the cord relay 127 to ground and back to battery. This circuit causes said sequence switch to move from its eighth position and this movement will be continued due to the special contact 156 until it comes to rest in its eleventh position. In this movement, however, there is completed a circuit through a restoring relay 270, which in turn through sequence switch contact 269 completes a circuit through the position sequence switch 265, causing same to move from its sixteenth into its seventeenth position. The circuit through said relay 270 may be traced from battery 172 through the winding of said relay, conductor 271, sequence switch contact 132, which is closed in the ninth and tenth positions of cord sequence switch 155, and by the special contact 156 of said cord sequence switch 155 to ground and back to

battery. The position sequence switch 265 in this seventeenth position closes contacts which complete circuits through the four registering devices causing them to move through the remainder of their cycle and to their normal position, the circuits being 70 severally traced from battery 172, through the motor magnets 401, 402, 403, and 404 of the several registers, through the respective register contacts 405, 406, 407 and 408, conductors 417, 418, 419 and 420 and the sequence switch contacts 280, 281, 282 and 283 to ground and back to battery. 75

It will be noted that the register contacts 405, 406, 407 and 408 are all closed at all times except when the respective registers 80 are in their normal positions and therefore the movement of all of the registers to normal will immediately begin when the sequence switch contacts 280, 281, 282 and 283 are closed by the position sequence switch. 85

As soon as the registers have all reached their normal or first position in which position none of the indicating lamps are lighted the register contacts 405, 406, 407 and 408 are opened and a circuit is completed from battery 172 through the power magnet of the position sequence switch 265, sequence switch contact 279, conductor 421, thousands register contact 422, hundreds register contact 423, tens register contact 90 424, units register contact 425, to ground and back to battery. The closure of this circuit causes the position sequence switch 265 to leave its seventeenth position and come to rest in its first or normal position 100 in which position the circuit just traced is again opened at the sequence switch contact 279. It should be noted that the energizing circuits, in response to the closure of which the respective registers move to normal, are all open at the contacts 405 to 408 in the first or normal position of such registers, and that each of them will therefore stop in its first or normal position. It should be further noted that the particular 105 order in which the registers reach normal position is immaterial, it only being necessary that each of them should have reached its normal position in order to close the circuit for the position sequence switch. The 110 four registers are now in their normal condition and the position sequence switch with its associated apparatus is also in normal position. There being no normal position for the cord finder itself no restoration 115 120 thereof is necessary. The position sequence switch and the registers are now free to be associated with and coöperate with some other cord circuit other than the one over which we have assumed the call was received, and such operation with some other cord circuit will in no way affect or interfere with the ringing of the desired line, 125

the establishment of the talking circuit or the restoration of the apparatus associated with the particular cord to normal.

Referring now particularly to Fig. 2 it will be recalled that the sequence switch has just passed from its eighth to its eleventh position. In the ninth, tenth and eleventh positions of this sequence switch, sequence switch contacts are closed to project ringing current out over the called line. The circuit of this ringing current may be traced from the grounded generator 133 through the ringing relay 134, sequence switch contact 135, one winding of the usual induction coil which inductively connects the two portions of the transmission circuit, conductor 136, ring contact of the plug, out over the line and back again through the tip contact of the plug, conductor 137, sequence switch contact 138 and to ground. This will cause the signaling of the subscriber on the desired line, who removes his telephone receiver from the switch hook thereby permitting in the usual way such an increase of current to pass that the ringing relay 134 will be energized thereby and attract its armature. Circuit will thereupon be closed from the battery 172 through the power magnet of the cord sequence switch 155, conductor 110, sequence switch contact 115, armature and front contact of the ringing relay 134 to ground and back to battery. The cord sequence switch will thereupon move from its eleventh position into its twelfth position which is the talking position and in which the sequence switch contacts 175, 176 and 177 are closed. The closure of the sequence switch contacts 175 and 176 has bridged across the inner terminals of the induction coils associated with the plug end of the connecting circuit a battery and a supervisory relay 178. This supervisory relay will be maintained energized so long as the called subscriber's receiver remains off the receiver hook. A circuit will be established by the attracted armature of the supervisory relay 178 from the battery 172 through the second supervisory relay 105, conductor 179, sequence switch contact 177, front contact and armature of the supervisory relay 178 to ground and back to battery. The energization of the second supervisory relay 105 has opened the original bridge across the trunk end of the cord circuit which included the line relay 103 and battery, and has substituted another bridge including the line relay alone. This bridge may be traced from the conductor 35 through the sequence switch contact 181, conductor 107, conductor 106, line relay 103, armature 104 and its front contact of the second supervisory relay 105, armature 109 and its front contact of the same relay 105, conductor 108, sequence switch contact 182

and to conductor 36. The second supervisory relay has furthermore by its armature 109 and front contact bridged around the line relay a condenser 180. The line relay owing to the absence of battery will now be deenergized.

At the same time that the bridge including the line relay 103 is changed by the second supervisory relay, the armature 184 of this relay is attracted to prevent the energization of the sluggish supervisory relay 185 which now through the sequence switch controls the operation of the lamp 122 which acts as a disconnect signal. The circuit of this sluggish supervisory relay extends from the battery 172 through the sequence switch contact 186, sluggish supervisory relay 185, conductor 187, to armature 184 of the second supervisory relay 105, and thence through either the front contacts of this armature and the armature of the line relay or through the back contacts of such armatures to ground and back to battery. That is to say, to energize the sluggish supervisory relay 185 it is necessary that the second supervisory relay 105 and the line relay 103 be both energized or both deenergized. The sluggish relay 185 is made sluggish for the purpose of avoiding detrimental effects if by chance the line relay should remain momentarily energized after the energization of the second supervisory relay 105 in response to the attraction of the armature of the first supervisory relay 178. Conversation may now continue between the calling line and the called line as long as may be desired, the battery for the called subscriber being supplied from the battery 172 as indicated, it being noted that the springs 101 and 102 were shifted from the sequence switch contacts 195 and 196 to the sequence switch contacts 181 and 182 so as to include in the circuit the windings of the induction coil when the cord sequence switch moved from its third to its fourth position. When, however, conversation is over and the called subscriber restores his receiver to the receiver hook the circuit of the supervisory relay 178 is opened and such relay thereupon retracts its armature. This opens the circuit of the second supervisory relay 105 which in turn retracts its armatures and closes the circuit of the sluggish supervisory relay 185. This circuit being maintained the sluggish supervisory relay attracts its armature which closes a circuit for the cord sequence switch 155 which may be traced from the battery 172 through the power magnet of the cord sequence switch, sequence switch contact 197, armature and front contact of the sluggish supervisory relay 185 to ground and back to battery. The cord sequence switch thereupon moves from its twelfth into its thirteenth position

and a circuit is thereupon established for the supervisory lamp 122 extending from the battery 172 through the supervisory lamp 122, sequence switch contact 198, 5 armature 184 and its rear contact of the second supervisory relay 105, back contact and armature of the line relay 103 to ground and back to battery. This illuminates the supervisory lamp 122 which attracts the 10 attention of the operator who thereupon knows that conversation has finished and that she may withdraw the plug from the jack of the called line. The operator thereupon withdraws the plug thereby destroying 15 the energizing circuit of the cord relay 127. This cord relay thereupon allows its armature to retract and a circuit is thereby established for the cord sequence switch 155 which may be traced from the battery 172 20 through the power magnet of the cord sequence switch, contact 199, conductor 151, back contact and armature 131 of the cord relay to ground and back to battery. The cord sequence switch thereupon moves from 25 its thirteenth position and comes to rest in its first or normal position, passing through without stopping the positions 14, 15 and 16 in which positions the sequence switch contact 152 is maintained closed to prevent the 30 opening of the trunk circuit, while the apparatus associated therewith at the manual exchange is being returned to normal. The entire apparatus is now again in its normal position and may be taken for use in connection with some other call as may be desired.

In case the operator at the semi-mechanical exchange desires to interrupt the call before the same has been completed she can 40 do so either in the second or the eighth position of sequence switch 155 by opening the circuit at the calling end of the line and permitting the armature of the line relay 103 to drop back into its normal position. 45 As will be seen in these two positions of the sequence switch 155 there will be closed a sequence switch contact 157 which, if the armature of said line relay is in its normal position will complete a circuit through the 50 locking relay 158, said relay being locked when once energized from the second to the twelfth position of sequence switch 155 through the sequence switch contact 186. The energization of the aforesaid relay will 55 close through its armature 159 and its front contact a circuit through the sequence switch 155, which circuit it will maintain closed continuously from the second to the twelfth positions of this sequence switch, 60 causing it to move into its thirteenth position thereby lighting the lamp 122 as a "knockdown" or disconnect signal for the operator at the manual exchange. Furthermore the movement of the cord sequence

switch due to the energization of the relay 65 158 will release the position sequence switch 265 which will thereupon be restored to normal and with it the registers precisely as occurred when the plug 124 was inserted 70 in the jack as above described. It should be noticed however, that when the relay 270 has once been energized whether as a result 75 of the insertion of the plug 124 in the jack or some act of the distant operator it will be maintained energized over the locking circuit from battery 172, relay 270 and its locking armature sequence switch contact 272 to ground and back to battery. Since the sequence switch contact 272 is closed in all 80 positions of the position sequence switch from 2 to 16 inclusive this sequence switch is positively prevented from becoming stalled in one of the intermediate positions and as soon as the registers have again reached normal will itself be returned to normal position. 85

It will be understood that while I have shown certain specific circuits and apparatus embodying my invention, my invention is not limited to such circuits and apparatus, but includes in its scope any arrangement of circuits and apparatus performing similar functions and included within the terms of the hereinafter appended claims. It will be further understood 90 that the showing of the controlling or calling apparatus at the originating exchange or station is partial and diagrammatic and includes only such parts and apparatus as are necessary for an understanding 95 of my invention and to typify the general character of the apparatus at the originating exchange or station with which the apparatus shown at the incoming exchange cooperates. It will be understood furthermore that this calling or controlling apparatus may be operated in any suitable manner, either manually or, preferably, automatically, it being only necessary that this apparatus, in the operations thereof hereinbefore described, be so operated or controlled that the parts are restored to normal and a new controlling circuit established 100 through one of the switches indicated and typified at 51, 52, 53, etc., within the interval while the position sequence switch 265 is moving from its third to its seventh position, again while this position sequence switch is moving from its seventh to its eleventh position, and again while it is moving 105 from its eleventh to its fifteenth position. To accomplish this operation within the proper time, any suitable or convenient means may be used, or the operator may attend to these operations manually, but since 110 the manner and means of accomplishing these operations form no part of my present invention, they will not be described herein. 115 120 125

Having described one embodiment of my invention what I claim is:

1. The combination with a plurality of talking circuits, of an automatic calling device for setting up the number of a desired telephone station, a registering device, means for automatically associating said device with any talking circuit taken for use and with said automatic calling device to disclose the number set up, and means for associating said register with another talking circuit while said first talking circuit is still in use.
2. The combination with a plurality of independent circuits, of a calling device connected with one of said circuits, a common registering device for registering the designation produced by said calling device, means to automatically connect said registering device with a circuit taken for use and to place said registering device under the control of said calling device, and means to free said registering device for common use while said line is still in use.
3. The combination with counting apparatus for automatic exchange apparatus, of lines connecting said counting apparatus with a manual exchange, numerical indicating apparatus at said manual exchange adapted to be associated with any one of said lines for indicating a call, said indicating apparatus embracing a plurality of registers, one for each digit of the number called, said registers being moved definite distances in response to said counting apparatus to determine corresponding digits of the number called, and indicating lamps brought into circuit in the operation of said registers to designate the number called.
4. The combination with calling mechanism for automatic exchange apparatus, of lines connecting said calling mechanism with a manual exchange, numerical indicating apparatus at said manual exchange embracing a plurality of successively operated registers each moved a definite distance in response to said calling mechanism to determine one digit of the number called, contact devices carried by each of said registers, and a bank of lamps for each of said registers, the lamp in each bank designating the digit determined by its corresponding register being lighted through a circuit completed by one of said contact arms.
5. The combination with calling mechanism for automatic exchange apparatus, of lines connecting said calling mechanism with a manual exchange, a cord at said manual exchange for each of said trunk lines terminating thereat, a numerical indicating apparatus at said manual exchange responsive to said calling mechanism, means for automatically associating said indicating apparatus with any one of said cords, and signaling means for designating to the operator with which cord said indicating apparatus is associated.
6. The combination with calling mechanism for automatic exchange apparatus, of lines connecting said calling mechanism with a manual exchange, a cord at said manual exchange for each of said trunk lines, a numerical indicating apparatus at said manual exchange responsive to said calling mechanism, switching means adapted to associate said indicating apparatus with a particular cord for purposes of receiving a call and signaling means operated by said switching means to designate the cord with which said indicating apparatus is so associated.
7. The combination with calling mechanism for automatic exchange apparatus, of lines connecting said calling mechanism with a manual exchange, a cord at said manual exchange for each of said lines, numerical indicating apparatus at said manual exchange responsive to said calling mechanism, switching means adapted to associate said indicating apparatus with a particular cord and means for finding the particular cord with which said indicating apparatus is associated.
8. The combination with calling mechanism for automatic exchange apparatus, of lines connecting said calling mechanism with a manual exchange, a cord at said manual exchange for each of said lines, numerical indicating apparatus at said exchange responsive to said calling mechanism, switching means adapted to associate said indicating apparatus with a particular cord, and means operated by said switching means for finding the particular cord.
9. The combination of semi-mechanical exchanges and a manual exchange, of trunk lines connecting said semi-mechanical exchanges with said manual exchange, a cord at said manual exchange for each of said trunk lines, a numerical indicating apparatus, switching means adapted to associate said indicating apparatus with a particular cord, means operated by said switching means for finding the particular cord, and a signal operated upon the completion of the cord finding apparatus to designate the particular cord in use.
10. The combination of a semi-mechanical exchange and a manual exchange, of trunk lines connecting the same, a numerical indicating apparatus at said manual exchange, means for automatically connecting said indicating apparatus with any one of said trunk lines for purposes of indicating a call, and means for automatically disconnecting it therefrom as soon as such call is completed.
11. The combination of a semi-mechanical exchange and a manual exchange, of trunk

- lines connecting the same, cords at said manual exchange one for each trunk line terminating thereat, each of said cords being provided with a plug, a numerical indicating apparatus adapted to be connected with any one of said cords for purposes of designating a call, and means for releasing said indicating apparatus from a particular cord, said means being controlled by the insertion 5 of the plug of that cord into a jack.
12. The combination of a semi-mechanical exchange and a manual exchange, of trunk lines connecting the same, a cord at said manual exchange for each of said trunk 15 lines, each of said cords being provided with
- a plug, a sequence switch associated with each cord, a numerical indicating apparatus, a second sequence switch adapted to associate said indicating apparatus with any one of said cords, and means, controlled by the insertion of the plug of that cord into a jack, operating said sequence switches to reset the recording apparatus preparatory to receiving a succeeding call. 20
- In witness whereof, I hereunto subscribe 25 my name this 17th day of Sept. A. D. 1910.
- FRANK R. McBERTY.
